UNITED STATES PATENT OFFICE.

JULIAN P. HILL, OF HAMBURG, NEW YORK.

BURIAL CASKET.

Application filed July 21, 1922. Serial No. 576,494.

This invention relates to improvements in burial caskets similar to that shown in Letters Patent of the United States No. 796,332, which generally comprises a cylindrical body of glass, covers applied to the end openings of the body, and a support for the remains of the deceased within the body.

One of the objects of this invention is to so construct the cover that the same is strong and durable and not liable to be broken while being handled or when applied to the body and also permit of producing a hermetical joint between the cover and body of the casket which will exclude air and moisture from the interior of the casket and thus protect its contents.

Another object of this invention is to provide simple and efficient means whereby the cover and body may be quickly and securely connected for closing the casket and still enable the same to be readily opened, if required, if a post mortem examination of the remains is necessary, or for other purposes.

A further object of this invention is to provide a support for the remains within the casket which is light and inexpensive and which is so connected with the covers of the casket that no undue strain or displacement will occur of the fastening means, whereby the covers are detachably connected with the internal support.

In the accompanying drawings: Figure 1 is a side elevation of my improved casket. Figure 2 is a horizontal longitudinal section of the same taken on line 2—2, Fig. 1. Figure 3 is a vertical longitudinal section taken on line 3—3, Fig. 2. Figure 4 is a vertical cross section taken on line 4—4, Fig. 3.

Figure 5 is a fragmentary vertical cross section, on an enlarged scale, taken on line 5—5, Fig. 2. Figure 6 is a longitudinal section of one of the covers and associated parts.

Similar characters of reference indicate corresponding parts throughout the several views.

In its general organization, this casket comprises an enclosing casing having a body and covers applied to opposite ends of the body, a support for the remains within the body, and means for securing the covers to the body and detachably connecting the same with the support within the body.

The body 10 is preferably constructed of

glass in the form of a cylinder of suitable length, diameter and thickness and having preferably, though not necessarily, an opening at each end thereof.

The end openings of the body are closed by covers and as these covers are preferably identical in construction, the following description of one will apply to both.

Each of these covers comprises an outer cap-shaped section of glass which has an outwardly dished crown 11 and an inwardly-projecting annular flange 12 at the margin of the crown, and an inner cap-shaped section of sheet metal which has an outwardly dished crown 13 and an inwardly projecting flange 14 at the margin of the last mentioned crown. These two cap-shaped sections of the cover are assembled so that the inner section is nested or telescoped within the outer section and the crown and flange of the inner sheet metal section engage with the corresponding parts of the outer glass section. These parts are preferably secured together by means of cement between them or by other suitable means. These two cap sections are applied so that the flanges thereof embrace the peripheral surface of the body at one end of the same and the bore of the flange of the metallic cap section engages the periphery of the body. By thus providing the glass section of the cover with an inner lining of sheet metal, the glass is strengthened or reinforced and prevented from breaking under ordinary strains while at the same time retaining the non-corroding properties of the glass.

The join between the cover and the body is preferably hermetically sealed so as to form an air and water tight joint between the same and thus protect the contents of the casket against contamination. This is preferably accomplished by making the flange of the metal cap section somewhat narrower than that of the glass cap section, so that the edge of the inner cap flange terminates short of the edge of the outer cap flange and forms an annular groove or channel 15 between these cap sections and the body. After the cover and body have been assembled, this groove is filled with a sealing material or cement 16, such for instance as a mixture of litharge and glycerine, thereby not only securely fastening the flange of the cover to the body but also excluding

air and moisture from the interior of the same.

For the purpose of increasing the security of the joint between the covers and the body, 5 cement is also placed between the inner side of the flanges of the inner metal cap section and the body. To interlock the cement with the body and the covers and still further strengthen or improve the joint between the 10 body and covers, the periphery of the body is sanded, roughened, grooved or corrugated for a suitable distance from each end thereof, as shown at 40 in Figs. 2 and 3, and the inner part of the bore of each of the glass 15 cap sections of the cover is provided with roughened, sanded, grooved or corrugated surfaces, as shown at 41, in Figs. 2, 3 and 6, whereby an anchorage for the cement is provided on these parts and not only a perfect 20 hermetic seal between the same is produced but a strong connection between the body and covers is attained which positively prevents separation thereof under the heaviest strains likely to be encountered.

25 In order to support the body internally at each end and reduce the possibility of crushing the same, a supporting ring 17, preferably of metal, is provided which engages with the bore of the body at one end opening 30 thereof and secured at its outer edge to the adjacent part of the inner metal cap section by brazing or otherwise, so that this supporting ring forms in effect part of the cover and is applied simultaneously to the body and removed therefrom with the cover, thereby 35 facilitating the closing and opening of the end of the casket.

The remains which are placed in the casket are preferably supported in a central 40 position therein by a bed which in its preferred form consists of a shell of light material, such as paper board, which consists of a semicylindrical lower wall 18 curved to correspond to the lower part of the body, and a flat horizontal top wall 19 connecting the upper edges of the bottom wall and arranged substantially diametrically relatively to the body, a filling 20 of light fibrous material, such as saw dust or excelsior arranged 45 in the shell and rendering the same sufficiently solid to support the remains which rest therein within the casket, and end walls 60 connecting the ends of the top and bottom and forming part of the shell.

55 Improved means are provided which mechanically fasten the covers to the body and to each other, and also serve as part of the support for the remains within the casket, which means, for example, may be constructed as follows:

21, 21 represent two horizontal retaining rods arranged lengthwise over the opposite longitudinal edges of the supporting bed. The corresponding pairs of ends of these 65 retaining rods are connected by cross bars

22 of metal each of which is provided midway of its length with a guide passage or opening 23 which is preferably square in cross section. Mounted on the inner side of each of the covers is a longitudinal coupling rod or shank 24 which has its inner part passing through the opening 23 in the adjacent cross bar 22 and is of corresponding square form in cross section, so that this rod can only slide lengthwise in the cross 75 bar but is incapable of turning therein.

At its outer end this coupling rod is provided with an external screw thread 25 which engages with an internally screw threaded metal socket 26 arranged on the central part of the crown of the sheet metal cap section and preferably connected therewith by soldering or brazing. On one side of its inner part this coupling rod is provided with a longitudinal row of ratchet shaped locking teeth 60 which are adapted to be engaged by a ratchet detent mounted on the adjacent part of the respective cross bar so as to permit the coupling rod to be moved inwardly but not outwardly. In its preferred form, this detent consists of a ratchet dog 27 which is guided in a casing 28 on the inner side of the adjacent cross bar, so that it is capable of sliding crosswise and which is provided at its front end with an abrupt inner face and an inclined outer face which are yieldingly held in the path of the ratchet teeth by a spring 80 interposed between the rear end of the dog and its casing.

The bed may be connected with the longitudinal retaining rods in any suitable manner but preferably by means which permit of depressing the bed under the weight of the remains resting thereon and thus enable the cross bars 22 to be always arranged in such a position that the coupling rods 24 may be moved lengthwise into engagement with the same upon slipping the covers onto the ends of the body of the casket. For this purpose, a metal band 29 is passed 105 around the underside of the lower bed wall at each end thereof and provided at opposite ends with two upright hangers or arms 30 which are secured to the adjacent ends of the retaining rod. The lower part of this band is held in place on the lower bed wall by a covering 31 of paper or other heat insulating material which is cemented 110 thereto, which paper also serves to keep the metal band out of contact with the glass body of the casket and thus avoids cracking the latter in the event of any difference in temperature between these parts or other conditions which might produce this objectionable result.

The arms or hangers 30 are preferably corrugated horizontally, so that these hangers can stretch more or less and permit the bed to settle the requisite extent under the load of the remains 115 120 125 130

resting therein and still permit the cross bars 22 to extend horizontally and diametrically across the body and in position to be engaged by the means which connect 5 the covers therewith.

After the remains have been placed on the bed of the support, the latter is pushed lengthwise into the cylindrical body of the casket and the longitudinal rods and cross bars of the same are adjusted vertically so that the guide openings in the cross bars are arranged in line with the axis of the casket. The cover is now applied to each end of the body by moving the cover longitudinally 10 inward on the body, so that the flanges of its outer and inner cap sections slip over the periphery of the body and the supporting ring slips into engagement with the bore thereof and the coupling rod passes 15 inwardly through the guide opening in the cross bar at the respective end of the casket. During this operation, the teeth of the coupling rod trip past the dog of the fastening or locking mechanism and when the cover has been pushed inwardly as far as possible, the dog engages its abrupt side with the corresponding side of the respective 20 ratchet tooth on the coupling rod and locks the cover against outward movement under a longitudinal pull. After the covers have 25 been thus locked upon the ends of the body, an air and water tight joint is produced between the same by filling the joists between the covers and the body with a suitable cement, whereby the contents of the 30 casket are effectively protected against the contaminating influences in the outer atmosphere.

If for any reason it is necessary to gain 35 access to the interior of the casket after the covers have been fastened thereto, this can be done by first removing the cement between the covers and the body and then rotating each cover backwardly so as to unscrew the socket of the same from the 40 threaded outer end of the respective coupling rod, thereby exposing the interior of the casket and permitting removal of its contents. Thereafter, the coupling rods 45 may be pushed to their full extent inwardly through the cross bars and again screwed on the sockets of the covers preparatory to again applying the covers to the body.

Removal of the covers is ordinarily not 50 necessary, one of the few instances when this would be required being the necessity of readjusting the remains in the casket in the event that the same has become displaced during shipment from one place to another. When such displacement is likely 55 to occur, the covers are preferably only sealed temporarily by an easily removable cement at the place from which the remains are shipped, so that the casket can be readily opened at its destination for readjust-

ing the remains and then permanently sealed with strong cement preparatory to interment.

In actual use, this transparent container or enclosure for the remains is placed with 70 in a separate cabinet of wood, metal or other material having the general form of caskets now commonly used.

The various improved features enumerated herein render a casket of this type 75 more durable and ensure greater safety for the remains deposited therein, they permit of conveniently and reliably closing the casket preparatory to interment or otherwise disposing of the same, they permit of 80 thoroughly sealing the casket while at the same time permitting access thereto, if required, and the same can be readily manipulated and manufactured economically.

I claim as my invention:

1. A casket comprising a cylindrical body having an end opening, a support within the body, a cover extending across said opening, and a fastening adapted to be arranged within the body and to connect said cover and support by moving said cover lengthwise on said body. 85

2. A casket comprising a cylindrical body having an end opening, a support within the body, a cover extending across said opening, and a fastening adapted to be arranged within the body and to connect said cover and support by moving said cover lengthwise on said body and to disconnect 95 said cover and support by a relative rotary movement of said cover and body. 100

3. A casket comprising a cylindrical body having an end opening, a support within the body, a cover extending across said opening, and a fastening adapted to be arranged within the body and to connect said cover and support and comprising a bar arranged on said support and having a passage, a coupling rod connected at its outer end with said cover and having its inner end passing through said passage, and a ratchet locking device interposed between said bar and rod. 105 110

4. A casket comprising a cylindrical body having an end opening, a support within the body, a cover extending across said opening, and a fastening adapted to be arranged within the body and to connect said cover and support and comprising a bar arranged on said support and having a passage, a coupling rod connected at its outer end with said cover and having its inner end passing through said passage, and a ratchet locking device interposed between 115 said bar and rod and comprising a plurality of ratchet teeth arranged in a longitudinal row on one side of said rod, and a spring pressed dog mounted on said bar and engaging said teeth. 120 125

5. A casket comprising a cylindrical body

- having an end opening, a support within the body, a cover extending across said opening, and a fastening adapted to connect said cover and support and comprising a coupling rod having a screw connected at its outer end with said cover, and a ratchet locking device connecting the inner end of said rod with said support.
6. A casket comprising a cylindrical body having an end opening, a support within the body, a cover extending across said opening, and a fastening adapted to connect said cover and support and comprising an internally screw threaded socket arranged on the inner side of said cover, a coupling rod having an externally threaded outer end which engages with said threaded socket, and a ratchet locking device connecting the inner end of said rod with said support.
7. A casket comprising a cylindrical body having an end opening, and a cover mounted on the end of the body and extending across said opening thereof and comprising an outer glass section, and a lining of metal on the inner side of the glass section.
8. A casket comprising a cylindrical body having an end opening, and a cover mounted on the end of the body and extending across said opening thereof and comprising an outer cap-shaped glass section, and an inner cap-shaped metal section secured to the inner side of said outer section.
9. A casket comprising a cylindrical body having an end opening, and a cover mounted on the end of the body and extending across said opening thereof and comprising an outer cap-shaped glass section, and an inner cap-shaped metal section secured to the inner side of said outer section, the flanges of said cap sections embracing said body.
10. A casket comprising a cylindrical body having an end opening, and a cover mounted on the end of the body and extending across said opening thereof and comprising an outer cap-shaped glass section, and an inner cap-shaped metal section secured to the inner side of said outer section, the flanges of said cap sections embracing said body and the flange of the metal cap section engaging its bore with the periphery of said body.
11. A casket comprising a cylindrical body having an end opening, and a cover mounted on the end of the body and extending across said opening thereof and comprising an outer cap-shaped glass section and an inner cap-shaped metal section secured to the inner side of said outer section, the flanges of said cap sections embracing said body and the flange of the metal cap section engaging its bore with the per-

iphery of said body, and a metal ring arranged on the inner cap section and engaging with the bore of said body.

12. A casket comprising a cylindrical body having an end opening, and a cover mounted on the end of the body and extending across said opening thereof and having an annular flange the outer part of whose bore is of small diameter and fits around the body while the inner part of its bore is of larger diameter and forms an annular groove between the cover and the exterior of the body, and a sealing cement arranged in said groove.

13. A casket comprising a cylindrical body having an end opening, and a cover mounted on the end of the body and extending across said opening thereof and comprising an outer cap-shaped glass section, and an inner cap-shaped metal section secured to the inner side of said outer section, the flanges of said cap sections embracing said body and the flange of the metal cap section engaging its bore with the periphery of said body and terminating short of the edge of the flange of the glass cap-section forming an annular groove between said flanges and the periphery of said body, and a filling of sealing material arranged in said groove.

14. A casket comprising a cylindrical body, and a support arranged within the body and comprising two longitudinal retaining rods arranged on horizontally opposite sides of the body, a bed arranged on the lower part of the body, and hangers connecting said bed with said rods and each constructed of a strip of corrugated metal.

15. A casket comprising a cylindrical body, and a support arranged within the body and comprising two longitudinal retaining rods arranged on horizontally opposite sides of the body, a bed arranged on the lower part of the body, a metal band passing around the underside of said bed and having its ends corrugated and extending upwardly to form hangers which are secured to said rods.

16. A casket comprising a cylindrical body, and a support arranged within the body and comprising two longitudinal retaining rods arranged on horizontally opposite sides of the body, a bed arranged on the lower part of the body, a metal band passing around the underside of said bed and having its ends extending upwardly to form hangers which are secured to said rods, and a heat insulating strip extending over that part of the band on the underside of the bed and secured to the latter.

JULIAN P. HILL.
